[57] CLAIM

The ornamental design for a shoe sole bottom and periphery, as shown and described.

DESCRIPTION

FIG. 1 is a perspective view of the shoe sole bottom and periphery;

FIG. 2 is a plan view of the shoe sole bottom;

FIG. 3 is a left side view of FIG. 2;

FIG. 4 is a rear side view of FIG. 2;

FIG. 5 is a top view of the shoe sole but is not a part of what is being claimed;

FIG. 6 is a right side view of FIG. 2;

FIG. 7 is a front side view of FIG. 2;

FIG. 8 is a cross-sectional view taken along line 8—8 of FIG. 2; and,

FIG. 9 is a cross-sectional view taken along line 9—9 of FIG. 2.

The broken lines shown in FIGS. 5, 8, and 9 are for illustrative purposes only and form no part of the claimed design.
